UNITED STATES PATENT OFFICE.

JOSEPH H. HAM, OF BRANTFORD, ONTARIO, CANADA.

AUTOMOBILE JACK.

Application filed February 17, 1922. Serial No. 537,242.

To all whom it may concern:

Be it known that I, JOSEPH H. HAM, a subject of the King of Great Britain, and resident of the city of Brantford, county of Brant, Province of Ontario, in the Dominion of Canada, have invented certain new and useful Improvements in an Automobile Jack, described in the following specification and illustrated in the accompanying drawings, that form part of the same.

The principal objects of the invention are, to facilitate the placing and operating of a jack under a car, thereby avoiding loss of time and inconvenience and other detrimental features of placing and operating the jack of the ordinary kind which requires the operator to reach under the car.

The principal feature of the invention consists in the novel construction and arrangement of parts, whereby the jack and operating crank therefor are rigidly mounted on a portable base and whereby said base is provided with a carrying handle placed in a balanced arrangement.

In the drawings, Figure 1 is a perspective view of my improved jack.

Figure 2 is a side elevational and part sectional view.

My improved construction of jack consists of a base 1 formed of a length of board sufficient to reach well under a motor car and upon this base is secured at one end the jack 2. This jack consists of a standard 3 which is securely bolted to the base and is provided with a threaded spindle 4 supported on a ball journal 5.

A sleeve member 6 slidable in the standard 3 is threaded on the spindle 4 and is provided with a spur projection 7 which extends through a slot 8 in the standard. This spur projection is arranged low down so that the jack may be utilized under a very low portion of the car structure in the event of a breakdown.

The upper end of the sleeve 6 is provided with a saddle 9 one side of which is formed with a hinge joint 10 and to this hinged joint is connected a block 11 which rests in the saddle and forms an extension which may be thrown back as shown in Figure 1, if desired.

The spindle is operated by a bevelled gear 12 secured to the lower end thereof and meshing with this gear is a pinion 13 which is journalled in an upward incline.

An operating rod 14 is connected to the stem of the pinion and this rod extends in an upward direction longitudinally of the base 1 and is supported at the outer end by a standard 15 carrying a pivotal sleeve 60 bearing 16 which eliminates the necessity for aligning the bearings.

A suitable crank wheel 17 is secured to the outer end of the rod 14. This is arranged at a height which enables it to be 65 very easily operated and the length of the board is such that when the jack is under the part to be raised the wheel will be clear of any of the overhanging portion of the car.

It will be readily seen that by reason of the mounting of the jack on a base and supporting the operating rod a distance from the jack enables the jack to be placed in position under the load without the necessity of the operator stooping and reaching under the car. In order to further facilitate the handling of this jack I provide a standard 18 arranged intermediate of the length of the base and so placed as to balance the jack. This standard is provided with a handle 19 at the top and also has a sleeve portion 20 through which the rod 14 extends and is supported thereby.

The advantages of the use of a jack such as described will be readily apparent and requires no further exemplification.

What I claim as my invention is:—

1. A jack, comprising, an elongated base, a lifting member rigidly arranged at one end 90 of said base, and an operating member connected with the lifting member and rigidly supported at the other end of the base.

2. A jack, comprising an elongated base, a lifting member secured at one end of the 95 base, a standard secured at the other end of the base, an operating rod connected with the lifting member and extending to and supported from the top of the standard at the other end of the base, and a crank member connected to the upper end of the rod.

3. A jack, comprising, an elongated base, a lifting member secured at one end thereof, a standard secured at the other end of said base and having a pivotal sleeve bearing, a 105 rod journalled in said sleeve bearing and extending to and connected with the lifting member, and a crank connected with the free end of the rod.

4. A jack, comprising a base formed of a 110

plank, a lifting member secured to one end of the plank, a standard secured to the other end of said plank, an operating rod extending from the lifting member to the top of said standard and journalled therein, a crank on said operating rod, and a standard provided with a handle secured to the base and in balance between the ends.

5. A jack, comprising a base, an operating handle supported from the base, a lifting member connected with the operating handle having a slotted standard, and a spur on the moveable end of the lifting member extending through the slot in the standard.

JOSEPH H. HAM.
